Primary Examiner—Susan Bennett Hattan*(74) Attorney, Agent, or Firm*—Corzen O'Connor**(57) CLAIM**

I claim the ornamental design for an aerosol dispenser cap, as shown and described.

DESCRIPTION

FIG. 1 illustrates a right side front perspective view of an aerosol dispenser cap with a cover showing my new design, the left side front perspective view being a mirror image of the right side front perspective view;

FIG. 2 illustrates a left side view of an aerosol dispenser cap showing my new design, the right side view being a mirror image of the left side view;

FIG. 3 illustrates a rear view of an aerosol dispenser cap showing my new design;

FIG. 4 illustrates a front view of an aerosol dispenser cap showing my new design;

FIG. 5 illustrates a top view of an aerosol dispenser cap showing my new design; and,

FIG. 6 illustrates a bottom view of an aerosol dispenser cap showing my new design.

The broken lines showing of the underside of the aerosol dispenser cap depict environmental subject matter only and form no part of the claimed design.
